UNITED STATES PATENT OFFICE.

DON L. THOMPSON, OF SPOKANE, WASHINGTON.

BATH-CABINET.

1,342,474.

Specification of Letters Patent.

Patented June 8, 1920.

Application filed January 23, 1918. Serial No. 213,355.

To all whom it may concern:

Be it known that I, DON L. THOMPSON, a citizen of the United States, residing at Spokane, in the county of Spokane, State 5 of Washington, have invented certain new and useful Improvements in Bath-Cabinets; and I do hereby declare the following to be a full, clear, and exact description of the invention, such as will enable others skilled in 10 the art to which it appertains to make and use the same.

This invention is an improvement in bath cabinets and has particular reference to a hot air and steam cabinet.

15 In the treatment of patients, in cabinets of the class herein specified, it often becomes desirable to use dry heat together with the steam or vapor since, by so doing, a patient is better enabled to withstand a higher degree 20 of heat than when only steam is employed.

It is proposed, in the present invention, to provide an improved means of using dry heat in connection with the steam for heating the interior of the cabinet.

25 Another object is to provide a cabinet of this character, which is simple in construction, easy to manufacture and effective in carrying out the purpose for which it is designed.

30 The inventive idea involved is capable of receiving a variety of mechanical expressions some of which, for the purpose of illustrating the invention, are shown in the accompanying drawing, wherein:

35 Figure 1 is a side elevation, partly broken away, of the cabinet constructed in accordance with the invention.

Fig. 2 is a fragmentary longitudinal section.

40 Fig. 3 is a transverse section on the line 3—3 of Fig. 1.

Fig. 4 is a view similar to Fig. 2 showing a slightly different form of the invention.

45 The cabinet is illustrated as comprising a body portion 5 having the usual supporting legs 6 and provided at one end with a head rest 7 for supporting the head of the patient whose body is lying within the cabinet. As 50 the construction of the cabinet just described forms no particular part of the present invention, it is to be expressly understood that any form of cabinet may be employed.

55 The invention resides in mounting the main steam pipe 8 within the space below the compartment in which the patient lies

and above the bottom of the cabinet, said pipe extending longitudinally of the cabinet and having one end connected to a spout 9 of a kettle 10, or other receptacle mounted upon a gas stove or other source of heat 11 so that the water in the kettle may be raised to the boiling point to generate steam which enters the pipe 8 through the spout 9. The end of the pipe 8 remote from the spout 9 is 60 bent upon itself to provide a steam outlet pipe 12 having a row of longitudinally aligned openings 13 in the bottom thereof for permitting the steam in the pipe to escape into the cabinet. The object of using the two additional pipes 12 and 14 is to give greater 65 dry hot air radiating surface. The placing of the pipes one above the other, a longitudinal position, in coil like fashion and the placing of the openings 15 on the lower side 70 of the lower pipe tends to hinder or obstruct the free flow of steam through the pipes thus augmenting the amount of dry heat radiated by said steam. The escaped steam from the openings 13 will mix with the dry 75 heat radiating from the pipes, and thus temper the steam as it comes in contact with the occupant of the cabinet and it is for the purpose of increasing dry heat radiation and of facilitating the mixture of the dry heat and steam that the pipes 8 and 12 are arranged 80 in superposed or vertically aligned relation.

When it is desired to increase the dry heat, radiation, the pipe 12 is made without the openings 13 therein and a steam outlet pipe 14 shown in Fig. 4 is connected to the free 90 end of the pipe 12 and extends horizontally in a plane directly beneath said pipe and adjacent the bottom of the cabinet, said pipe 14 having a row of aligned openings 15 in the bottom thereof to permit of the steam and water of condensation in the pipe escaping. Thus by providing a greater radiating surface it will be apparent that a greater 95 amount of dry heat will be produced which will mix with the steam arising from the 100 opening 15.

It is apparent also that by driving the steam downwardly instead of permitting it to rise through the coil, the pressure of the steam is slightly raised with a consequent 105 increase in temperature while any vapor that escapes from the drain openings in the bottom sections of the coil will, in rising, come in contact with the very hot coils and will be raised in temperature and further 110 expanded so as to not dampen the atmos-

sphere to which the body of the patient is subjected. In other words, any vapor that rises in the lowermost coil must of necessity pass from one hot pipe to the one next above where it will be so dried out and expanded as to raise the temperature of the air in the cabinet without dampening it to any degree that can be appreciated.

What is claimed is:—

- 19 1. A bath cabinet comprising a hollow body portion having a patient receiving compartment in its upper portion and a steam conveying pipe entering the body portion and including a plurality of mutually connected sections disposed one below another beneath the patient-receiving compartment, the lower-most section having a series of outlet openings located longitudinally of its lower-most portion for passage of live steam therefrom upwardly of both sides of the section to both sides of the sections thereabove, the pipe being otherwise without an outlet.
- 15
- 20

2. A bath cabinet comprising a hollow body portion having a patient receiving compartment in its upper part and a steam conveying pipe entering the body portion and including a plurality of mutually connected sections disposed one below another, for passage of steam downwardly therethrough, the sections being in mutually spaced relation beneath the patient-receiving compartment, and the lowermost section having a series of outlet openings located longitudinally of its lowermost portion positioned for passage of live steam therefrom upwardly of both sides of the section to both sides of the sections thereabove, the pipe being otherwise without an outlet.

In testimony whereof, I affix my signature in the presence of two witnesses.

DON L. THOMPSON.
